CLAIM

The ornamental design for a low profile light, as shown and described.

DESCRIPTION

FIG. 1 is a perspective view of a low profile light according to a first embodiment of the present invention;

FIG. 2 is a top plan view of the low profile light illustrated in FIG. 1.

FIG. 3 is a bottom plan view of the low profile light illustrated in FIG. 1.

FIG. 4 is a side elevation of the low profile light illustrated in FIG. 1.

FIG. 5 is a perspective view of a low profile light according to a second embodiment of the present invention;

FIG. 6 is a top plan view of the low profile light illustrated in FIG. 5.

FIG. 7 is a bottom plan view of the low profile light illustrated in FIG. 5; and,

FIG. 8 is a side elevation view of the low profile light illustrated in FIG. 5.

The broken lines depict elements of the low profile light that do not form a claimed feature of the present invention.

1 Claim, 4 Drawing Sheets

Related U.S. Application Data

No. 14/134,884, filed on Dec. 19, 2013, now Pat. No. 8,947,844, which is a continuation of application No. 13/476,388, filed on May 21, 2012, now Pat. No. 8,672,518, which is a continuation-in-part of application No. 12/775,310, filed on May 6, 2010, now Pat. No. 8,201,968.
